UNITED STATES PATENT OFFICE.

ATTILIO GIAILEVER, OF S. MARGHERITA LIGURE, ITALY.

EXPLOSION-PUMP.

1,285,678.

Specification of Letters Patent. Patented Nov. 26, 1918.

Application filed April 27, 1915. Serial No. 24,331.

To all whom it may concern:

Be it known that I, ATTILIO GIAILEVER, engineer, subject of the King of Italy, residing at S. Margherita Ligure, Italy, have 5 invented certain new and useful Improvements in Explosion-Pumps, of which the following is a specification.

The present invention relates to a water pumping device of the kind in which the 10 power for the direct pumping of water is obtained by the explosion of any gas, separate chambers being provided for the compression of the gas and the production of an explosion. The subject matter of the application 15 differs from these known devices owing to the fact that the compression chamber is provided above the level of the liquid to be raised and is connected with the rising pipe of the explosion chamber through the 20 medium of a compound valve controlled by the column of water oscillating to and fro, while for controlling the valve for the compressed gas, for the ignition of the same and for the exhaust valve, a float is provided 25 within the compression chamber.

An arrangement of this kind has the advantage of being very simple and having a safe operation.

In the accompanying drawings:

30 Figure 1 is a sectional side elevation of my pump showing the beginning of the explosion stroke.

Fig. 2 discloses the reservoir or chamber being filled.

35 Fig. 3 illustrates the position of the various parts of the apparatus, as the same will appear at the completion of the explosion stroke.

Fig. 4 discloses various details in side 40 elevation and section of the explosion apparatus which serves to compress the fluid and force the same to a high level.

Fig. 5 illustrates parts, such as disclosed in Fig. 4, but in front elevation.

45 Fig. 6 is a detail view disclosing the structure of the compound valve utilized in connection with this device.

The device consists of an explosion chamber A which is provided with the bottom 50 valves 8 and 9. Between the latter there terminates the rising pipe C, D opening into a receptacle E provided with the outlet pipe h.

The compression chamber B is located 55 above the explosion chamber A in such a manner that it is always above the water

level, said compression chamber communicating on the one hand, with the rising pipe C and on the other, with the pipe D, and in addition thereto is provided with the outlet 60 pipe b leading to the well. At the connecting point of the pipes, a compound valve 5, 6, 7 is provided which is controlled by a single spindle. The movement of the valve 5, 6, 7 is effected by the levers u, u' mounted 65 on the axis i, which levers u, u' are operated by the manually actuated chain m. The chamber B is connected with the chamber A by the tube c provided, at its ends, with the valves 3 and 1, the former of which is operated by a cam x keyed on the axis p of a float d located in the chamber B. Upon the same axis and externally of the said chamber, a cam s is provided, engaged by the pin of a traction rod g to which the exhaust 70 valve 2 of the explosion chamber A is connected. q is the contact of a lead f' leading to a source of current from which another lead f leads to the sparking plug e. The cam s has such a configuration that in a certain 75 position it touches the contact q.

The device operates in the following manner:

In the operative position, the device is plunged into the liquid to the requisite 80 depth. The liquid enters through the valves 8, 9 into the explosion chamber A until it has reached the outer level, air escaping at the same time through the valve 2. The small body of water necessary to start the working 85 of the apparatus is filled into the receptacle E in any desired well known manner until the receptacle E and the compression chamber B and the pipe D are full and water leaves through the pipe h. At this moment 90 the valve 5, 7 is raised from its seat by a manually operated chain m by means of which the lever u, u' is operated whereby the valve 6 is closed and the pipes D, C are 95 opened. Water can now flow out of the 100 chamber B through the channel b, as the valve 5 has been opened at the time the valve 6 was closed and effect a suction of gas through the pipe a while at the same time the float d sinks and the valve 3 is closed 105 through the medium of the cam x. After the liquid has been let out, the valves 5 and 7 are allowed to resume their seats by their own weight after the interruption of the manual operation of chain m whereby the 110 valve 6 is opened so that the liquid can reach the chamber B through the pipe D and raise

the float *d* and effect the introduction of gas through the valve 1 into the chamber A, the gases being prevented from escaping into the pipe *a* by the valve 4. When the float has re-assumed its original position, an electric circuit is closed by the sector *s*, contact *q* and leads *f*, *f'* thus producing at the sparking plug *e* a spark for the ignition of the gas contained in the chamber A.

10 From this moment, the device begins to operate constantly and automatically. While the explosion is being produced, the pressure resulting from the expansion of the burnt gases, and acting on the surface of the liquid 15 in the chamber A, will close the valves 8 and 9 whereas the valve 7 will open under the action of the liquid flowing through the pipes C, D and through the outlet pipe *h*. The valve 5 which opens at the same time, allows 20 the water to flow out of the chamber B whereby fresh gas is drawn in through the pipe *a*. The float *d* sinks and its cam *s* mounted on the axis *p* and the rod *g* connected therewith, produce the opening of the 25 exhaust valve 2. When the pressure of the exploded gases ceases, the returning liquid is prevented from re-entering the chamber A through the valve 7 which dropping down onto its seat produces the opening of the 30 valve 6 and the closure of the valve 5. Water is thereby forced to enter the chamber B through the valve 6 and again press the gas through the pipe *c* into the chamber A, raises the float *d* and produces a spark at the sparking plug. In the meantime, the deposits of 35 the burnt gases are expelled through the exhaust valve 2 and water can re-enter through the valves 8 and 9. The explosion takes place, the above described stages are 40 repeated and the device acts automatically and continuously.

It follows from the above description that owing to the special arrangement of the explosion and compression chambers and their 45 connection by means of a compound valve, the chamber B can be readily emptied and the valves are safely operated by the liquid. The ignition is produced in a safe and adjustable manner at the required moment, directly dependent upon the action of the 50 raised liquid. Gas is also drawn in in a uniform and safe manner independently of the height through which the liquid must be raised. Finally the exhaust of the gases 55 takes place adjustably and completely.

What I claim is:

1. A water pumping device of the character described comprising in combination, an explosion chamber A provided with bottom 60 valves 8, 9, a compression chamber located above said explosion chamber and the level of the water and provided with a gas inlet *a*, means 4 for controlling said gas-inlet, an auxiliary water supply E, a pipe extending 65 from and affording communication between

the explosion chamber and compression chamber and a further pipe extending from and affording communication between the explosion chamber and auxiliary water supply, an outlet at the bottom of the compression chamber, a double-acting compound valve 5, 6, 7 for alternately controlling the connection between the compression and explosion chambers said outlet and the water supply, a float *d* within said compression 70 chamber, a gas supply pipe *c* connecting the upper parts of said compression and explosion chambers, valves 1 and 3 for controlling the gas supply to said explosion chamber, one of said valves being adapted to be operated 75 by said float, an electric circuit *f*, *f'*, a spark plug *e* in said circuit and explosion chamber, and means *x* connected to said float for opening and closing said circuit, a gas escape valve 2 on top of said explosion chamber 80 and a rod *g* connected to said valve and said circuit closing and opening means for allowing the escape of the exploded gases and means *m* for manually controlling the operation of the means for alternately controlling the connections between explosion 85 and compression chamber and the water outlet of the latter, substantially as described and for the purpose set forth.

2. A water pumping device of the character described, comprising in combination, an explosion chamber A provided with bottom valves 8, 9, a compression chamber B located above the level of the water and provided with a gas-inlet *a*, a valve 4 for controlling 90 said gas inlet, an auxiliary water supply E, a pipe extending from and affording communication between the explosion chamber and compression chamber and a further pipe extending from and affording communication 95 between the explosion chamber and auxiliary water supply, a double-acting compound valve 5, 6, 7 for alternately controlling the connection between the compression and explosion chambers said outlet and the 100 water supply, a float *d* within the compression chamber, a gas supply pipe *c* connecting the upper parts of said compression and explosion chambers, valves 1, 3 for controlling the gas supply to said explosion chamber one 105 of said valves adapted to be operated by said float, an electric circuit *f*, *f'*, a spark plug *e* in said circuit and explosion chamber, and means *x* connected to said float for opening and closing said circuit, a gas escape valve 2 110 on top of said explosion chamber and a rod *g* connected to said valve and said circuit closing and opening means for allowing the escape of the exploded gases and means *m* for manually controlling the operation of 115 the means for alternately controlling the connections between explosion and compression chamber and the water outlet of the latter, substantially as described and for the purpose set forth.

3. A water pumping device of the character described comprising in combination, an explosion chamber A provided with bottom valves 8, 9, a superposed compression chamber B located above the level of the water and provided with a gas-inlet *a*, means 4 for controlling said gas-inlet, an auxiliary water supply E, a pipe extending from and affording communication between the explosion chamber and compression chamber and a further pipe extending from and affording communication between the explosion chamber and auxiliary water supply, an outlet *b* at the bottom of the compression chamber, a double-acting compound valve 5, 6, 7 for alternately controlling the connection between the compression and explosion chambers and said outlet, a float *d* within the compression chamber, a gas supply pipe *c* connecting the upper parts of said compression and explosion chambers, valves 1 and 3 for controlling the gas supply to said explosion

chamber, one of said valves being adapted to be operated by said float, an electric circuit *f*, *f'*, a spark plug *e* in said circuit and explosion chamber, and a cam *x* connected to said float for opening and closing said circuit, a gas escape valve 2 on top of said explosion chamber and a rod *g* connected to said valve and said cam for allowing the escape of the exploded gases, and chain operated levers *u* *u'* for manually controlling the operation of the means for alternately controlling the connections between explosion and compression chamber and the water outlet of the latter, substantially as described and for the purpose set forth.

In testimony whereof I have affixed my signature in presence of two witnesses.

ATTILIO GIAILEVER.
